UNITED STATES PATENT OFFICE.

JOHN WILLIAM POINTON, OF BURSLEM, ENGLAND, ASSIGNOR TO MADDOCK & MILLER, OF NEW YORK, N. Y., A CORPORATION OF NEW YORK.

DESIGN FOR A PLATE OR SIMILAR ARTICLE.

No. 39,214.

Specification for Design.

Patented March 24, 1908.

Application filed February 24, 1908. Serial No. 417,609. Term of patent 7 years.

To all whom it may concern:

Be it known that I, JOHN WILLIAM POINTON, a subject of the King of Great Britain, residing at Burslem, Staffordshire, England, have invented a certain new, original, and ornamental Design for Plates or Similar Articles, of which the following is a specification.

In the accompanying drawing the figure is a plan showing the design of the plate.

What I claim is
The ornamental design for a plate, or similar article, as shown.

JOHN WILLIAM POINTON.

Witnesses:

WILLIAM HENRY TAYLOR,
JOHN HENRY COPESTATE.
